UNITED STATES PATENT OFFICE.

FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

DISTRIBUTOR FOR IGNITION APPARATUS.

1,417,717.

Specification of Letters Patent. Patented May 30, 1922.

Application filed September 13, 1919. Serial No. 823,570.

To all whom it may concern:

Be it known that I, FRANK CONRAD, a citizen of the United States, and a resident of Pittsburgh, in the county of Allegheny and State of Pennsylvania, have invented a new and useful Improvement in Distributors for Ignition Apparatus, of which the following is a specification.

My invention relates to internal-combustion engines and particularly to ignition systems for such engines.

One object of my invention is to provide an ignition system for internal-combustion engines, having a plurality of spark plugs per cylinder, that shall be reliable under all conditions of operation.

Another object of my invention is to provide an ignition system for such engines that shall employ a relatively small number of exposed wires to connect the source of energy to the rotating contact arm and that may permit the utilization of a compact unitary structure.

In practicing my invention, I provide a plurality of contact terminals mounted in the usual distributor box corresponding, in number, to the spark plugs in the engine and connected thereto. The contact terminals are arranged in a definite order, determined by the number of cylinders in the engine. The usual induction coil is provided and its terminals are connected to two approximately semi-annular contact plates mounted in the distributor box. A two-part rotating distributor arm is provided having two brushes on each part, one of each of these brushes being adapted to engage the contact plates, and the other to engage the contact terminals. The angle between the two parts of the arm and the connection of the contact terminals to the spark plugs in the engine is such that the two spark plugs of each cylinder are fired at the same time, and all of the spark plugs are fired in the proper sequence, as required by the firing order, during one complete revolution of the contact arm.

In the single sheet of drawings, Figure 1 is a sectional view of a distributor box, rotating arm and shaft mounting embodying my invention, with certain parts shown in side elevation, and Fig. 2 is a top plan view, partly in section, of the device embodying my invention. Fig. 3 is a diagrammatic view of the circuits used with the

device embodying my invention, while Fig. 4 is a similar view of a modification.

Referring to Fig. 1, a metal supporting box 10 is provided with an extension 11 to enable it to be suitably mounted on the internal-combustion engine with which it is associated. An arm 12 is provided to enable the box 10 and the mechanism contained therein to be turned through a small angle to advance or to retard the spark. The extension 11 has a cylindrical hole 13 drilled therethrough in which is placed a rotatable shaft 14. The shaft 14 is rotated, by suitable means, (not shown) from the engine shaft and is properly timed therewith. A collar 15 is secured to the shaft 14, near its outer end, by means of a pin 16, and a collar 17 is fitted on the shaft 14 at the inner end of the extension 11 and held thereon by means of a pin 18. The two collars 15 and 17 hold the shaft 14 in place in the cylindrical hole 13. A cam 19 is mounted on the shaft 14, immediately adjacent to the collar 17, and is secured to the collar by means of a pin 20 so that it will rotate therewith and with the shaft 14. A spring ring 21 serves to press the cam 19 against the collar 17 and to retain it in its proper position.

An interrupter 22, operated by the cam 19, is shown generally only and may be of any well known type. A condenser 23 is mounted in the box 10 and is connected, in the usual manner, to the interrupter.

An insulating casing 24 is mounted on the box 10 and is provided with a cover member 25. Mounted in the casing 24, are the primary winding 26 and the secondary winding 27 of a usual induction coil. The terminals of the primary winding are connected to suitable contact terminals 28 suitably mounted in the casing 24 and the box 10. Two approximately semi-annular contact plates 29 are mounted in the insulating cover member 25 and are connected, by wires, (not shown) to the terminals of the secondary winding 27.

A removable insulating cover 30 is provided for the casing 24, having a plurality of contact terminals 31 mounted therein, each being provided with an insulated head 32. Spring clips 33 are provided to hold the cover 30 on the casing 24. At the upper end of the shaft 14, is mounted a rotatable insulated arm 34 comprising two parts which have a definite angular relation to each other.

other. Near the outer end of each part, is mounted a suitable brush 35 fitted into a metal tube 36 and pressed outwardly by a spring 37, so as to operatively engage the inner surfaces of the contact terminals 31. A brush 38, similar to the brush 35, is provided in each part of the arm 34 intermediate the shaft and the brush 35 to engage the contact plates 29. The brushes 35 and 38, in each part of the rotatable arm 34, are electrically connected together by suitable means, here shown as a metal plate 39. A suitable source of energy 40 is provided which is controlled by a manually operated switch 41.

As shown in Figs. 2, 3 and 4, I have illustrated the apparatus embodying my invention as used in connection with a six-cylinder engine having two spark plugs per cylinder. The 12 contact terminals 31, mounted in the cover 30, are arranged in alternate sets, those numbered 1, 2, 3, 4, 5 and 6 being connected to one set of spark plugs, and those numbered 1', 2', 3', 4', 5' and 6' being connected to the other set of spark plugs of the six cylinders, the numbers referring to the firing order. I have shown only two spark plugs, which are connected to the contact terminals 5 and 5', but it is understood that similar connections are made from the other contact terminals to the corresponding spark plugs of the engine.

If the cam 19 of the interrupter is adjusted to energize the circuit at the time that the rotating arm 34 is in the position shown in Fig. 2, it may be noted that the brushes 38 are engaging the contact plates 29, and the brushes 35 are engaging the contact terminals, numbered 1 and 1', and that, therefore, the two spark plugs belonging to that cylinder will be fired simultaneously. Assuming a clockwise rotation of the arm 34 in Fig. 2, the circuit will be again energized when the arm is moved through an angle such that the brushes 35 will engage the contact terminals 2 and 2'. It will be seen that the contact terminals 31 will be numbered 1, 4', 2, 5', 3; 6', 4, 1', 5, 2', 6, 3', if the arm is assumed to rotate in a clockwise direction.

The angular distance between the contact terminals 1 and 1', in a distributor box to be used with a six-cylinder engine, may have any one of a number of definite values determined in accordance with the number of spark plugs which are, in turn, dependent upon the number of engine cylinders. The two brushes 35 may be so spaced as to engage adjacent contact terminals, in which case the angular distance between the two brushes will be 360° divided by the number of spark plugs (12), that is, 30° . In this case, the two brushes 35 will engage the contact terminals now marked 1 and 3', it being understood that these contact terminals will

be connected to the two spark plugs associated with one engine cylinder. If one of the brushes 35 is so located as to engage contact terminal number 1 in Fig. 2, the other brush 35 may be so located as to engage any one of the contact terminals 3', 2', 1', 6', 5' or 4', provided proper connections are made between the contact terminals and the spark plugs. The angular distance between the two brushes 35, as measured in degrees, may be 30° , 90° , 150° , 210° , 270° or 330° in a distributor box designed for use with a six-cylinder engine, and may be 45° , 135° , 225° or 315° in a distributor box designed for use with a four-cylinder engine. The auxiliary brushes 38 must be located diametrically opposite each other and be so located in relation to the semi-annular contact plates as to be energized at the proper times, and also be properly connected to the brushes 35. While, as stated above, the angle between the two brushes 35 may have any one of a number of definite values, in accordance with the number of spark plugs, I have chosen to illustrate the design which results in the best running balance of the arm.

While it may be sufficient to use only one induction coil and one interrupter, I do not wish to be restricted to this, as it may be necessary, at times, to use a plurality of interrupters and of induction coils, and I have shown the diagram of connections for such condition in Fig. 4. I may use either the plurality of cams 19, as there shown, or arrange to actuate both interrupters from a single cam.

While I have shown a specific application of my invention, it is apparent that modifications may be made without departing from the spirit and scope of my invention, and I desire that only such limitations shall be placed thereon as are imposed by the prior art or are specifically set forth in the appended claims.

I claim as my invention:

1. In a distributor device, the combination with a plurality of contact terminals and two stationary and approximately semi-annular contact plates adapted to be periodically energized, of a two-part rotatable distributor arm having a plurality of brushes on each part, one of the brushes on each part being adapted to engage the contact terminals successively and the other brush on each part being adapted to engage the stationary contact plates successively.

2. In a distributor device, the combination with a plurality of contact terminals, of two stationary and substantially semi-annular contact plates adapted to be periodically energized, a two-part rotatable arm, two brushes on said arm coacting with said contact plates successively, and two brushes mounted on said arm for engaging said contact terminals successively, said brushes be-

ing spaced apart an angular distance to be determined in accordance with the number of contact terminals.

3. In a distributor device, the combination with a plurality of series of contact terminals mounted therein, of two stationary and substantially semi-annular contact plates adapted to be periodically energized, a two-part rotatable distributor arm, two 10 electrically connected brushes on each part of the arm, one of the brushes on each part being adapted to engage the contact terminals successively and the other brush on each arm being adapted to engage the contact 15 plates successively, said brushes being angularly spaced in accordance with the number of contact terminals.

4. In a distributor device, the combination with an induction coil, a source of current, and an interrupter for said induction coil, of a set of contact terminals mounted in said distributor, a second set of contact terminals mounted in said distributor and alternating in position with the first set of 25 contact terminals, two substantially semi-annular contact plates connected to said induction coil, a two-part rotatable contact arm, a plurality of electrically connected brushes on each part of said arm, one brush 30 on each part of said arm being adapted to engage said contact plates successively, and the other brush on each part of said arm being adapted to engage the contact terminals successively, the angle between the 35 two parts of said arm being such that the brushes will engage contact terminals of different sets.

5. In a distributor device for an engine having a plurality of spark plugs per cylinder, the combination with a source of current, an induction coil, an interrupter for said induction coil, a set of contact terminals mounted in said distributor, a second set of contact terminals mounted in said 45 distributor and individually alternating in position with those of the first set and spark plugs connected to all of said contact terminals, of two substantially semi-annular con-

tact plates connected to said induction coil, a two-part rotatable contact arm, a plurality of electrically connected brushes mounted on each part of said arm for connecting the contact plates to the contact terminals, the angle between the two parts of said contact arm being such that the brushes will engage 50 contact terminals of different sets, whereby the two spark plugs connected to one cylinder will be simultaneously energized.

6. In an ignition system for internal-combustion engines having a plurality of spark plugs per cylinder, the combination with a distributor box, a plurality of contact terminals mounted in said box, an induction coil, and an interrupter for said induction coil, of two substantially semi-annular contact plates mounted in said box to which the terminals of said induction coil are connected, a shaft extending into said box, a rotatable contact arm mounted on said shaft and located within said box, a plurality of brushes mounted on said arm and adapted to so connect said contact plates to said contact terminals as to energize the same in a predetermined order.

7. In an ignition system for internal-combustion engines having a plurality of spark plugs per cylinder, the combination with a distributor device having two sets of contact terminals, those of one set being disposed in alternation with respect to those of the others, connections from said contact terminals to corresponding sets of spark plugs, the contact terminals connected to the spark plugs of one cylinder being located such angular distance apart as shall be determined by the total number of spark plugs, of two stationary substantially semi-annular contact plates mounted in said distributor device, a rotatable arm, and two sets of brushes mounted on said arm for operatively connecting said contact plates to said contact terminals in predetermined order.

In testimony whereof, I have hereunto subscribed my name this 3rd day of Sept., 1919.

FRANK CONRAD.
